WASTE RECEPTACLE OR THE LIKE

Floyd H. Panning, 3146 N. Frederic St.,
Burbank, Calif. 91504

Filed Mar. 4, 1969, Ser. No. 16,031

Term of patent 14 years

Int. Cl. D7—99

U.S. Cl. D49—35

FIG. 1

FIG. 2

FIG. 3

FIG. 1 is a perspective view of a waste receptacle or the like showing the new design from one side;

FIG. 2 is an elevation as seen from the opposite side of FIG. 1; and

FIG. 3 is a fragmentary enlarged view of FIG. 2.

The characteristic features of my design for a waste receptacle, resides in the specific configuration of the swinging door member as best illustrated in FIGS. 1 and 3.

I claim:

The ornamental design for a waste receptacle or the like, substantially as shown and described.
